WEARING SHOES FOR ORE SEPARATORS

Edmund C. Bitzer, Denver, Colo., assignor to
Colorado Iron Works Company, Denver, Colo.,
a corporation of Maine

Application October 27, 1950, Serial No. 192,479

6 Claims. (Cl. 209—464)

1

This invention relates to ore separators and more particularly to wearing shoes employed on the spiral flights of the conveyors for same and is a continuation-in-part of my copending application, Serial No. 173,406, filed July 12, 1950, now abandoned.

In ore separators, such as the well-known Akins type, it is common practice to provide replaceable wearing shoes on the peripheral edges of the spiral conveyor flight or flights. These shoes are usually formed with smooth circular outer edges and a substantially flat raking face. In operation, they form a smooth cylindrical trough of abrasive ore in the classifier tank which abrades the outer edges of the shoes causing the edges to wear more rapidly than the raking faces, and as they wear to smaller diameter the raking capacity of the classifier is reduced.

One of the objects of this invention is to provide an improved wearing shoe which is more resistant to wear.

Another object is to provide a shoe which wears more evenly on its various parts.

Another object is to reduce the friction load between the wearing shoes and the ore bed, thus reducing power requirements.

A further object is to rake the ore bed in a novel manner which improves drainage of liquid therethrough.

Still further objects, advantages, and salient features will become more apparent from a consideration of the description to follow, the appended claims, and the accompanying drawing, in which:

Figure 1 is a fragmentary perspective of an ore separator, portions being shown in transverse section;

Figure 2 is a top plan of one form of wearing shoe which constitutes the subject of the invention;

Figure 3 is a side elevation of Figure 2 as viewed in the direction of arrow 3, portions being broken away;

Figure 4 is an enlarged section taken on line 4—4, Figure 3;

Figure 5 is a section taken on line 5—5, Figure 3, at a point wherein the wearing shoes engage the ore bed; and

Figure 6 is a top plan, similar to Figure 2, showing a modification of the invention.

Referring in detail to the drawing, and particularly Figure 1, the separator 10 comprises a tank 11 and a spiral conveyor flight 12 supported for rotation by shaft 13. The axis of

2

rotation 14 of the shaft 13 is inclined to the horizontal so that it moves material upwardly in the direction of arrow 15. The ore bed 16, previously referred to, is formed between the conveyor and tank, this forming the abrasive means which causes the shoes 17 to wear.

Referring to Figures 2 to 5, each shoe comprises a segment which has a face 18 the shape of the warped surface formed by a family of helices, the face forming a raking surface which moves material upwardly in the inclined tank. The periphery of the segment is provided with integral teeth 19, the teeth being formed with front faces 20 which are at an angle A to a radial line 21, that is, angle A may be termed a positive rake angle analogous to the positive rake angle of a cutting tool. The front face of each tooth is substantially rectangular, as best shown in Figure 4, the side edges of the teeth 20 being parallel as indicated by lines 22, 22a. Each tooth is also tapered in thickness as shown by line 23, being narrower at its leading face 20 than at its trailing portion 24. The outer surfaces of each tooth have a portion 25 which is substantially circular and a non-radial portion 26, as best shown in Figure 3.

The toothed segments are secured to the conveyor flight in any desired manner, such as by flat headed screws 27, provided with nuts 28 which abut the trailing side of the flights, as best shown in Figure 4. Secondary inner shoes 29 may be similarly secured to the flights by screws 30, these shoes being adapted to take a portion of the wear, but not as much as the outer shoes. The shoes may be cast or otherwise formed of any hard material such as white iron.

In operation, the serrated or toothed shoes plow the ore bed 16 so that they move through a less consolidated abrasive mass rather than against a smooth, hard abrading surface. The flight rotates in the direction of arrow 31, and as shown in Figure 5, at least a portion of the trailing edge 32 is disposed in a plane indicated by line 34 which intersects, or is ahead of, the edge 22a of the next trailing tooth. It will be apparent that as the forward tooth moves through the ore bed 16 the material of the bed will be moved by the forward raking face 23 of a tooth in the direction of arrow 15, and when edge 22a, as shown in Figure 5, reaches the position of particle 16a, this and other particles of the bed will be engaged principally by the forward raking face 23 of the trailing tooth, rather than by its front face 20, which minimizes wear on the front

face 20 and effects the greater portion of wear on the forward raking face 23, this producing more uniform tooth wear to maintain the teeth of optimum shape.

The construction shown in Figure 6 is similar to the one previously described except that the teeth 19a taper in thickness on both sides, that is, forward edges 22b and 22c are both disposed between opposite faces of the shoe. As shown, the teeth are symmetrical about a perpendicular plane extending through their longitudinal axes but it is to be understood that the amount of taper on each side may be divided as desired, and of course, as shown in Figures 1 to 5, may be all on one side. The choice of taper will depend, among other things, on the pitch of the teeth and the helix angle thereof to effect a raking action as explained in connection with Figure 5.

Having described the invention, what I claim as new is:

1. An ore separator comprising an inclined tank containing ore and liquid, a rotatable ore moving member having a spiral flight disposed in the tank, and a plurality of wearing shoes secured to said flight adjacent its peripheral edge, said shoes having teeth thereon that extend beyond the peripheral edge and form means adapted to rake into and loosen an ore bed disposed between the flight and tank, whereby the bed is maintained unconsolidated, liquid drainage therethrough is increased, and frictional drag between the bed and wearing shoes is reduced.

2. A spiral flight for use with ore separators of the type wherein the flight is rotatably mounted in the tank and the tank is adapted to hold an ore bed between it and the flight, said flight comprising; a plurality of segmental wearing shoes secured to its edge forming a radial extension thereof, said shoes having teeth thereon that project beyond the peripheral edge of the flight and form means that rake into the ore bed and loosen the same.

3. A shoe in accordance with claim 2 wherein said teeth are thinner at their leading faces than at their trailing portions.

4. A shoe in accordance with claim 2 wherein the leading faces of the teeth are disposed at a positive rake angle.

5. A shoe in accordance with claim 2 wherein said teeth are thinner at their leading faces than at their trailing portions and the leading faces are disposed at a positive rake angle.

6. A wearing shoe for attachment to the spiral flight of an ore separator wherein the flight is mounted for rotation about an inclined axis in an inclined tank, the tank being adapted to hold an ore bed between it and the flight, said shoe comprising a plurality of accurate sections, each section having spaced teeth along its peripheral edge, said teeth being thinner at their leading faces than at their trailing portions and extend radially beyond the peripheral edge of the flight, the leading faces of the teeth having at least portions thereof disposed rearwardly of a plane extending perpendicular to said axis of rotation and intersecting a trailing portion of a tooth disposed forwardly thereof in the direction of movement of the teeth.
